UNITED STATES PATENT OFFICE.

WILLIAM F. DONNELL, OF JONESBORO, ARKANSAS.

MILK-CAN.

985,016.

Specification of Letters Patent. Patented Feb. 21, 1911.

Application filed March 19, 1910. Serial No. 550,419.

To all whom it may concern:

Be it known that I, WILLIAM F. DONNELL, a citizen of the United States, and resident of Jonesboro, county of Craighead, Arkansas, have invented certain new and useful Improvements in Milk-Cans, of which the following is a specification containing a full, clear, and exact description, reference being had to the accompanying drawings, forming a part hereof.

My invention relates to improvements in milk cans, the object of my invention being to construct a novel closure for milk cans and to arrange the locking devices for the closure in planes inside of the periphery of the closure so that when the can is rolled the locking devices will not be apt to be broken.

For the above purposes my invention consists in certain novel features of construction and arrangement of parts as will be hereinafter more fully described, pointed out in the claims and illustrated by the accompanying drawing, in which:

Figure 1 is a vertical, sectional elevation of the complete can illustrating the same in a closed and sealed condition; Fig. 2 is an elevation of the upper portion of the can and cover therefor showing the means for sealing the cover to the can; Fig. 3 is an enlarged, vertical, sectional elevation of the upper portion of the can showing the cover therefor in a position about to be closed for sealing; Fig. 4 is an elevation similar to Fig. 2 illustrating the opposite end of the closing and sealing means; and Fig. 5 is a detail perspective illustrating a portion of the cover.

Referring by numerals to the accompanying drawing: 1 designates the main body portion of the can which is preferably cylindrical and 2 designates the bottom of the can which is united with the main body portion on a curved line as shown.

As shown in the drawing the bottom 2 is provided with a horizontal flat portion and is made separate from the body portion.

Secured to the can, preferably by riveting to the body portion 1, adjacent its lower margin, is a base 3 which diverges toward its bottom margin so that the side margin of the base, adjacent the bottom, lies in a plane outside of the can proper.

4 designates a ring which is secured to the body portion 1 of the can adjacent its upper margin and 5 designates an integral extension of the ring which lies in a plane some

little distance removed from the periphery of the can proper, the extension 5 uniting with the ring proper on a curved line and the upper margin of the extension 5 terminates in a plane flush with the upper margin of the can proper. The ring 4 and extension 5 together with a portion of the wall of the can proper form a pocket in which the continuous yielding gasket 6 is seated, which gasket is of a height normally greater than the height of the pocket.

7 designates the cover for the can which is provided with an annular down-turned extension 8, the extension uniting with the cover on a curved line. Portions of the extension 8 are removed on opposite sides of the cover forming openings 9 and 10.

11 designates a hinged hasp which is secured to the cover 7 in alignment with the opening 9. The free member of the hasp is provided with an opening 12 adjacent its lower end which is designed to embrace the projection 13 secured to the can proper. The pendant portion of the hasp 11 is arranged to occupy the opening 9 in the cover when in a position with the opening 12 engaging with the projection 13. Diametrically opposed to the hasp 11 is a hasp 14 which is secured to the cover 7 so that its pendant portion will occupy the opening 10 in the cover when in a closed position. Carried by the pendant portion of the hasp 14 is a cam 15 having an integral handle 16 which is slotted at 17. The end of the cam 15 is arranged to normally occupy a seat 18 formed in the ring 4.

19 designates a perforated ear which is secured to the body portion 1 of the can in a position to be embraced by the slot 17 of the cam handle.

20 designates a seal or lock which is arranged to be inserted through the perforation formed in the ear 19 for locking the cam handle in a closed position.

By reason of the construction of the can and cover therefor, as shown and described, it is obvious that the same may be perfectly cleansed for the reason that there are no angles opposing such perfect cleansing.

In view of the fact that the can is supplied with a rounded or partially rounded bottom it is obvious that an extraneous base is necessary to cause the can to stand erectly.

The base as shown not only performs the function of holding the can in an upright position but by reason of its being extended

outwardly adjacent its lower margin approximately to the same diameter as the cover 7 the can may be rolled on the base and cover and it is obvious that if any obstruction is met during such rolling the same will not contact with the body portion 1 of the can but be met by the cover or the base.

While I have shown and described the body portion 1 of the can and bottom therefore made of two pieces, I do not wish to be understood as limiting myself to this construction for the reason that the construction of a can having the can proper and bottom of a single piece lies within the scope of my invention.

The gasket 6 may be made of any yielding substance but I prefer to construct a gasket of soft rubber, the gasket being of a height greater than the height of the pocket in which it is held.

As shown in Fig. 3 the cover 7 is in a position to be sealed and locked, the hasp 11 at the left hand end of the can being secured in place over the projection 13.

It is obvious that by manipulation of the handle 16 and by reason of the cam 15 the gasket 6 will be compressed and occupy a position wholly within the pocket as shown in Fig. 1. After the lever has been moved to its sealing position the slot 17 therein will embrace the perforated ear 19, and to hold the lever in a locked position any ordinary seal or lock may be employed. After the can has been sealed and locked as shown the joint between the cover and the can is liquid-tight and by reason of said lock or seal the contents are safe against unauthorized removal.

I claim:

1. In a milk can, the combination with an open-topped uniform diametered, cylindrical can, of a ring secured to the periphery of the can adjacent its upper margin, an integral extension of said ring forming an annular pocket, a gasket located in said pocket, a cover having a down-turned flange, hasps carried by the cover, means for detachably securing one of the hasps to the can, means connected with the other hasp for moving the cover to compress said gasket in said pocket and means for locking the hasp and cover in a closed position.

2. In a milk can, the combination with an open-topped uniform diametered, cylindrical can, of a ring secured to the periphery of the can adjacent its upper margin, an integral extension of said ring forming an annular pocket, a gasket located in said pocket, a cover having a down-turned flange, hasps carried by the cover, means for detachably securing one of the hasps to the can, means connected with the other hasp for moving the cover to compress said gasket in said pocket and means for locking the hasp and cover in a closed position, said down-turned extension of the cover overlapping the integral extension of the said ring and provided with cutaway portions to accommodate portions of said hasps.

In testimony whereof, I have signed my name to this specification, in presence of two subscribing witnesses.

WILLIAM F. DONNELL.
